CLAIM

The ornamental design for a support accessory, as shown and described.

DESCRIPTION

FIG. 1 is a perspective view taken from the top, front and left side of a support accessory showing my new design, the embodiment being in the form of a towel ring;

FIG. 2 is a front elevational view thereof;

FIG. 3 is a right side elevational view thereof, the left side elevational view being the mirror image thereof;

FIG. 4 is a top plan view thereof;

FIG. 5 is a bottom plan view thereof;

FIG. 6 is perspective view taken from the top, front and left side of a support accessory showing my new design, the second embodiment being in the form of a rolled paper holder;

FIG. 7 is a front elevational view thereof;

FIG. 8 is a right side elevational view thereof, the left side elevational view being the mirror image thereof;

FIG. 9 is a top plan view thereof; and

FIG. 10 is a bottom plan view thereof.

The fragmentary broken line representations of walls in FIGS. 1 and 6 are for the purpose of illustration only and form no part of the claimed design.
